UNITED STATES PATENT OFFICE

JOHN W. MOOMAU, OF WEST ALLIS, WISCONSIN, ASSIGNOR OF ONE-HALF TO GEORGE W. STAUSS, OF MILWAUKEE, WISCONSIN

SAFETY DEVICE FOR BURNERS

Application filed July 3, 1929. Serial No. 375,773.

This invention relates to improvements in safety devices for burners.

One of the objects of my invention is the provision of a safety device designed to prevent accidental manipulation of the gas control valve and also to automatically close the valve in the event that the flame of the burner should be accidentally extinguished.

Another object of my invention is the provision of a device of the above character wherein the operating mechanism is controlled by a thermostatic member actuated by the heat from the burner and includes locking means which is actuated by the valve for positioning the locking means in operative position, but provides for manipulation of the valve handle of the locking mechanism.

A further object of the invention is the provision of a safety device of the above character wherein, when the burner is lighted, the thermostatic member will actuate a locking element for retaining the controlling rod in operative position and the valve is connected to the controlling rod in such manner as to permit movement of the valve handle of the controlling rod and whereby the locking mechanism is automatically disengaged should the flame of the burner be accidentally extinguished so that the controlling rod will be returned to its inoperative position and close the valve through operative connection thereto.

With the above and other objects in view, the invention consists in the novel features of construction, the combination and arrangements of parts hereinafter more fully set forth, pointed out in the claims and shown in the accompanying drawings wherein:

Figure 1 is a bottom plan view of a burner, illustrating the application of my improved safety device;

Figure 2 is a side elevation;

Figure 3 is a transverse section on the line 3—3 of Figure 2 with parts omitted.

Referring more particularly to the drawings, it will be noted that I have illustrated a burner 1 of any general type having a tubular fuel conduit 2 leading therefrom to a mixing tube 3 with a fuel inlet nipple 4

connected to the mixing tube. The fuel inlet nipple carries a valve 5 having a handle 6 whereby the fuel to the burner can be readily controlled.

Mounted upon the conduit 2 is a tubular supporting element 7 formed with transverse recesses in one end for receiving the contour of the conduit 2 whereby the member 7 can be easily seated upon said conduit.

Arranged at one side of the burner is a supporting plate 8 having a lateral extension 9 which extends over one end of the member 7 and the outer end of the extension 9 is rounded off so as to conform to the tubular shape of member 7. The lateral extension 9 is secured to the tubular member 7 through the medium of bolts 10 which extend down through the extension 9 and through a washer plate 11, nuts 12 being threaded onto the bolts against the outer face of washer plate 11 for retaining tubular member 7 and plate 8 against movement.

The plate 8 has at its end opposite the lateral extension 10, an arcuate arm 13 which extends around the burner 1 preferably at the outside thereof whereby the arm 13, plate 8 and extension 9 provide a substantially arcuate-shaped portion extending around the greater portion of the burner. Extending across the burner above the same is a thermostatic member 14, one end of which is secured to an adjustable plate 15 at the outer end of arm 13, while the other end of the thermostatic member 14 is connected to a movable arm 16 carried by the main body portion of the plate 8.

The plate 15 is pivotally connected to the extremity of arm 13, as shown at 17, and the inner end of the plate is formed with a lateral flange 18 carrying a set screw 19, the inner end of which engages the outer contour of arm 13. Mounted upon the set screw 19 and disposed between the flange 18 and the finger piece 20 is a coil spring 21 which serves to retain the pin 19 in various adjusted positions.

It will be noted that by adjusting plate 15, the movement of the thermostatic member 14 is controlled whereby the amount of movement to the arm 16 is varied. It will also be

noted that in a great many instances, the thermostatic members 14 will expand and contract in a greater or less degree and it is therefore necessary to provide some means for adjusting the thermostatic member in accordance with its area of expansion and contraction.

The movable arm 16 is pivotally mounted on pin 22 carried by plate 8 and arranged adjacent to pin 22 is a pin 23 to which the inner end of the thermostatic member 14 is connected. This pin 23 extends through a slot 24 in plate 8, said slot being formed to accommodate the movement of the pin during the expansion and contraction of member 14. Slidably mounted upon the underside of plate 8 adjacent the outer edge thereof, is a control rod 25, said rod being slidably mounted within suitable bearings 26 and 26', beneath the plate 8 and mounted on the rod is a coil spring 27 disposed between bearing 26 and a cross pin 28 carried by the rod whereby to normally position the rod in an inoperative position, as shown at Figure 1.

The movable arm 16 has secured to its outer end an angular locking member 29, the lateral portion of which projects from arm 16 and is adapted to engage a notch 30 formed in rod 25 when the rod is projected to an operative position; a spring 31 engaging the lateral portion of member 29 carried by arm 16 for urging this locking member toward the notch 30 when the member 14 expands by the flame from the burner 1, so that the lateral extension of the locking member will positively engage the notch and retain rod 25 in an operative position.

Rod 25 is provided at its outer end with a lateral extension 32 and connected to the end of this lateral extension is a rod 33 which is connected to the handle 6 of the valve 5 whereby it will be noted that when the valve 5 is operated to admit fuel to the burner 1, the rod 25 through movement of the valve handle will be pulled downwardly against the tension of the spring 27. As soon as the fuel issuing from the burner 1 is lighted, the flame from the burner valve will cause the thermostatic member 14 to expand, actuating arm 16 so as to move the locking member 29 into position for engaging notch 30, whereby rod 25 will be maintained in an expanded or operative position. In view of the fact that the rod 33 is connected to the extension 32 in such manner as to permit sliding movement of the rod in one direction, the valve 5 may be readily manipulated for controlling the flame of the burner when the rod 25 is in an expanded position. If, however, the flame of the burner is extinguished in an accidental manner, the thermostatic member 14 will contract, operating arm 16 and disengaging the locking member 29 from notch 30 whereby the tension of spring 27 will actuate rod 25 to return the same to its innermost

position, and due to the connection between the rod 25 and handle 6, the valve 5 will be closed, thus cutting off the supply of fuel to the burner.

It will also be noted that by this improved safety device, should the valve be accidentally opened through an object striking the handle 6, the valve will be automatically closed by the tension of spring 27 as the locking means is only operated through the actuation of thermostatic member 14. Attention is also directed to the fact that the amount of movement of member 14 when expanded or contracted, can be readily controlled by set screw 19.

It will be apparent from the foregoing that I have provided a simple and inexpensive safety device which can be attached to various types of burners and will positively assure the closing of the controlling valve when the burner is not in use and will prevent accidental opening of the valve, and at the same time is so constructed that it can be quickly and readily installed.

While I have shown and described the preferred embodiment of my invention, it will be apparent that slight changes may be made in the construction when putting the invention into practice without departing from the spirit of the same or the scope of the appended claims.

I claim:

1. A device of the class described including a burner, a valve for controlling fuel to the burner, a thermostatic member acted upon by the flame from the burner, a spring actuated rod slidably mounted adjacent the burner and having a notch therein, a connecting rod operatively connected to the valve and slidably connected to the spring actuated rod, means controlled by the thermostatic member for retaining the spring actuated rod in a position in which the valve is opened when the burner is lighted including an arm connected to the thermostatic member, a locking member integral with and movable with the arm and adapted to engage the notch to retain said rod against movement, said locking member being released from the spring actuated rod through action of the thermostatic member when the flame is extinguished whereby the tension of the spring will be actuated to close said valve.

2. In combination, a stove burner having a supply pipe extending therefrom, and a burner valve in said pipe provided with a handle, a substantially L-shaped plate, means to secure one arm of the plate to the burner supply pipe with the other arm of the plate located adjacent the burner, a rod slidably supported by the last mentioned arm, a spring to yieldingly resist movement of the rod in one direction, a wire connecting the valve handle with the outer end of the rod to

5 tension the spring when the valve is in open position, a trigger slideable transversely of the plate, means providing a detachable engagement between the trigger and rod to hold the latter against inward movement, and a thermostatic element located adjacent the burner to actuate the trigger and release the rod.

10 In testimony that I claim the foregoing I have hereunto set my hand at Milwaukee, in the county of Milwaukee and State of Wisconsin.

JOHN W. MOOMAU.
